United States Patent Office

Des. 224,992
Patented Oct. 31, 1972

224,992

OVERSHOE

Mary K. Iskyan, 34—15 74th St.,
Jackson Heights, N.Y. 11372

Filed Dec. 14, 1970, Ser. No. 26,459

Term of patent 14 years

Int. Cl. D2—04

U.S. Cl. D2—279

FIG. 1 is a side perspective view of an overshoe showing my new design; and

FIG. 2 is a rear elevational view thereof.

I claim:

The ornamental design for an overshoe, as shown.
